US00D954114S

(12) **United States Design Patent** (10) **Patent No.:** **US D954,114 S**
(45) **Date of Patent:** **** Jun. 7, 2022**

(54) **REFRIGERATOR**

(71) Applicant: **SAMSUNG ELECTRONICS CO., LTD.**, Suwon-si (KR)

(72) Inventors: **Junkyo Lee**, Suwon-si (KR); **Hyeongju Seo**, Suwon-si (KR); **Jichang Kang**, Suwon-si (KR)

(73) Assignee: **SAMSUNG ELECTRONICS CO., LTD.**, Gyeonggi-Do (KR)

(**) Term: **15 Years**

(21) Appl. No.: **29/727,785**

(22) Filed: **Mar. 13, 2020**

(30) **Foreign Application Priority Data**

Sep. 16, 2019 (KR) 30-2019-0044309

(57) **CLAIM**

The ornamental design for a refrigerator, as shown and described.

DESCRIPTION

FIG. 1 is a front perspective view of a refrigerator, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

(Continued)

The broken lines illustrating portions of the refrigerator form no part of the claimed design.

1 Claim, 8 Drawing Sheets
